UNITED STATES PATENT OFFICE.

JOSEPH STOLZ, OF BERLIN-CHARLOTTENBURG, GERMANY, ASSIGNOR TO WESTING-
HOUSE ELECTRIC & MANUFACTURING COMPANY, A CORPORATION OF PENNSYL-
VANIA.

DISCONNECTING SWITCH.

Application filed October 1, 1925, Serial No. 59,844, and in Germany November 1, 1924.

My invention relates to electrical circuit interrupting devices and particularly to disconnecting switches.

One object of my invention is to provide a disconnecting switch that shall be capable of easily and efficiently breaking a mantle of ice surrounding the contact jaws.

Another object of my invention is to provide a disconnecting switch of the pivoted type, in which the contact members are given a local relative turning movement before the main movement of separation takes place.

A further object of my invention is to provide a disconnecting switch of the pivoted insulator type in which the initial turning movement of the supporting insulator is utilized for the purpose of disrupting the ice mantle surrounding the contact members and the remaining portion of the turning movement is utilized for separating the contact members.

Disconnecting switches are frequently mounted out of doors in climates where they are subject to heavy falls of sleet and the resulting accumulation of heavy mantles of ice. Such switches are supported on insulators that are usually of porcelain or the like and that are capable of withstanding heavy compression stresses, but are relatively weak under tension and torsional strains or torque. When such insulators are caused to move a switch blade out of an ice-covered switch jaw, it frequently happens that a quantity of ice is placed under compression in the switch jaw, with the result that very large bending moments must be applied to the insulator in order to open the switch. Ice, however, is relatively weak under tension.

Accordingly, I propose to initially pry the switch jaws apart in a direction such as to place any obstructing ice under tension, and thereby crack it before attempting to move the switch blade out of the switch jaw. I accomplish this result by providing the insulating support with a lug cooperating with a second lug on the switch blade, such that the initial turning movement on the insulator turns the switch blade about its longitudinal axis, after which movement the entire switch blade moves about the axis of the

insulator during the movement of the separation of the contact members.

In the accompanying drawings,

Figure 1 is an elevational view of a disconnecting switch embodying my invention.

Fig. 2 is an enlarged fragmentary view, in elevation, of the operating details of my invention.

Fig. 3 is a sectional view of the operating mechanism, taken along section line III—III of Fig. 2.

Fig. 4 is a plan view of the supporting insulator and plate attached thereto.

Fig. 5 is a sectional view of the switch blade and jaw in their closed position.

Fig. 6 is a similar view of the switch blade and jaw showing their relative positions during the initial movement of circuit interruption.

My invention comprises, in general, a base 1 on which are mounted stationary supporting insulators 2 and a rotatable supporting insulator 3, the former insulators supporting switch jaws 4 and the latter insulator supporting an elongated switch blade 5 for cooperation with the contact jaws 4 together with an operating mechanism 6, hereinafter more fully described. While I have shown the rotatable insulator 3 in combination with a pair of stationary insulators 2, it is obvious that it is capable of use with but a single stationary insulator.

The rotatable insulator 3 is surmounted by a cap 7 to which is attached a plate 8 by means of bolts 9 passing through elongated slots 11. The bolts 9 seat loosely in the slots 11 in order that relative movement may be had between the cap 7 and the plate 8. The cap 7 is provided with an upstanding lug 12 having a sloping face that constitutes a portion of the operating mechanism 6. A suitable operating rod 13 passes through the base 1 from the insulator 3 for attachment to a handle or other operating mechanism, (not shown).

The operating mechanism 6 comprises a pair of upright perforated lugs 14 formed on the plate 11 through which the switch blade 5 extends, together with a sleeve 15 that is disposed about the blade 5 between the flanges 14. The sleeve 15 is secured to the switch blade 5 by a set screw 16 and is pro-

vided with an outwardly projecting lug 17 that cooperates with the lug 12 heretofore described. When the inclined face of the lug 12 is moved under the lug 17, the switch blade 5 is turned about its longitudinal axis.

Referring particularly to Figs. 5 and 6, the switch blade 5 terminates in square faces 18 that normally fit snugly between the switch jaws 4, but which, when the switch blade 5 is turned about its longitudinal axis, serve to pry the switch jaws 4 apart in the manner shown in Fig. 6. If the switch jaws 4 are covered with a mantle of ice, their separation by the movement of the square portions 18 serves to place such ice under tension and to crack it, rather than necessitating the removing of the ice by straight compressive forces with the necessarily increased turning moments on the insulator 3.

20 In the circuit-opening movement of a disconnecting switch embodying my invention, a turning movement is given to the operating rod 13, and the insulator 3 and cap 7 are turned while the plate 11 remains stationary 25 by reason of the engagement of the jaws 4 and the contact blade 5. As the cap 7 turns, the lug 12 moves under the lug 17, and by reason of the inclined face of the former, the latter is lifted thereby turning the contact blade 5 30 with the result that the square ends 18 pry the contact jaws apart, as is shown in Fig. 6. This turning movement continues until the screws 9 engage the ends of their associated slots 11, which position is so designed that 35 the lug 12 does not pass by the lug 17. Further turning movement of the insulator 3 is transmitted through the screws 9 and plate 11 directly to the contact blade 5 which moves out from between the contact jaws 4.

40 During closing movement of the disconnecting switch, the lug 12 is first moved from under the lug 17 and the square portions of the contact blade 5 assume the relative angular positions to the contact jaws 4 shown in 45 Fig. 5.

Further turning movement of the insulator 3 causes the square portions 18 to enter the contact jaws 4, thereby closing the disconnecting switch.

50 It will thus be seen that I have devised a disconnecting switch wherein the initial opening movement serves to break under tension, any ice that may have accumulated in the contact jaws, after which the additional 55 turning movement of the insulator serves to disconnect the contact members. The stresses placed upon the operating and supporting insulator are accordingly materially reduced by eliminating the necessity for 60 breaking the ice mantle by compressive forces, as would be necessary were the ice not initially broken by being placed under tension.

It will be understood that such modifications in the arrangement and disposition of the several parts may be made as fall within the scope of the appended claims.

I claim as my invention:

1. In a switch structure, a pair of contact jaws, an axially rotatable contact member having means for spreading the jaws when axially rotated during opening movement and a pivotal support for one of the contact members comprising means for turning one of the contact members about its axis prior to the separation of the contact members.

2. In a switch structure, a jaw member, an axially rotatable blade member having means for spreading the jaws when axially rotated during opening movement, and a pivotal support for one of the members, the pivotal support comprising means for initially turning the supported member about the latter's axis.

3. In a switch structure, a jaw member, an axially rotatable blade member having means for spreading the jaws when axially rotated during opening movement, and a pivotal support for one of the members, the pivotal support comprising means for initially turning the supported member about the latter's axis in advance of the turning movement about the pivotal support to separate the members.

4. In a switch structure, a rotatably mounted insulator, a plate for the insulator having relative movement thereto, a member rotatably supported by the plate, and means for turning the supported member about an axis other than that of the insulator during relative movement between the insulator and the plate.

5. In a switch structure, a rotatably mounted insulator, a plate for the insulator having relative movement thereto, a member rotatably supported by the plate, a lug on the supporting member, and a cooperating lug on the insulator, whereby upon rotation of the insulator, the lugs coact to initially turn the supported member about its axis whereupon the several parts turn about the axis of the insulator.

6. In a switch structure, a rotatably mounted insulator, a plate for the insulator having relative movement thereto, a contact member movably supported by the plate, a cooperating stationary contact member, a lug on the first named contact member, and a cooperating lug on the insulator, whereby, upon initial turning movement of the insulator, the lugs engage and rotate the supported contact member, after which the several parts turn about the axis of the insulator.

In testimony whereof, I have hereunto subscribed my name this 8th day of September, 1925.

JOSEPH STOLZ.
